UNITED STATES PATENT OFFICE.

EDWIN S. WOODS AND ARNOLD A. WEIGEL, OF CHICAGO, ILLINOIS; SAID WEIGEL
ASSIGNOR TO SAID WOODS; ALBERT G. WELCH EXECUTOR OF SAID WOODS, DE-
CEASED.

ANTIFRICTION SIDE BEARING.

1,111,119.

Specification of Letters Patent.

Patented Sept. 22, 1914.

Application filed November 8, 1912. Serial No. 730,127.

To all whom it may concern:

Be it known that we, EDWIN S. WOODS and ARNOLD A. WEIGEL, citizens of the United States, and residents of Chicago, in the county of Cook and State of Illinois, have invented certain new and useful Improvements in Antifriction Side Bearings; and we do hereby declare that the following is a full, clear, and exact description thereof, reference being had to the accompanying drawings, and to the letters of reference marked thereon, which form a part of this specification.

This invention relates to improvements in side bearings for railway cars and the like and more particularly to improvements in antifriction side bearings which include rolling antifriction elements that are automatically returned by resilient means to a predetermined central or normal position, after they have been moved therefrom by the relative movement of the parts between which they are interposed.

The invention consists of the matters hereinafter described and more particularly pointed out in the appended claims.

In the drawings:—Figure 1 is a view representing a longitudinal central section through our improved side bearing. Fig. 2 is a view representing a top plan of our improved side bearing with the fixed cover plate of the case inclosing the same broken away intermediate its ends. Fig. 3 is an end elevation of our improved side bearing. Fig. 4 is a view representing a vertical transverse section through the side bearing in the plane indicated by the line 4—4 of Fig. 1. Fig. 5 is a view representing a vertical transverse section through our improved bearing in a plane indicated by the line 5—5 of Fig. 1.

Referring now to that embodiment of our invention illustrated in the drawings, 10 indicates a casing which incloses and supports the moving parts of the bearing. The said casing may be attached either to the body-bolster of the car or to the truck-bolster and, as shown herein, is attached to the body-bolster. The casing is oblong and rectangular in horizontal section and has upright side walls 11, 11 and upright end walls 12, 12. It is open at top and bottom and is provided with horizontal flanges 13, 13 at one open side, in this case its top side, and prefer-

ably at its ends, for attachment to the bolster with which it is connected.

14 indicates a fixed cover plate which, in the embodiment shown in the drawings, is attached to the top of the casing. Said cover plate extends over the flanges 13, 13 so that it may be secured to the casing by the same bolts 15, 15 that secure the casing to the bolster. The said cover plate preferably has depending grooved flanges 14^a, 14^a adapted for locking engagement with the beveled ends of the horizontal flanges 13, 13 of the casing. The flanges 13, 13 and the end parts of the fixed cover 14 are provided with suitable apertures to receive the bolts 15, 15.

16 indicates a wear-plate of hardened metal adapted to bear against the rolling antifriction elements contained in the casing. Said wear-plate is carried by the fixed cover plate 14 and is made, as shown, separate therefrom for purposes of renewal. The cover-plate is provided within the casing on its inner face with longitudinally extending lateral flanges 17, 17 and transversely extending end flanges 18, 18 which embrace the edges of the wear-plate 16, and the ends 16^a of the wear plate are beveled and the end flanges 18, 18 are bent inwardly, in a familiar manner, to engage said beveled ends so as to support the wear-plate.

The open part of the casing opposite the fixed cover 14 is closed by a movable cover plate 19. Said movable cover plate has at each side an upright longitudinally extending rib or flange 19^a provided with a longitudinally extending horizontal flange or shoulder 20 which is adapted for engagement with an inwardly extending longitudinal shoulder or track 21 on the side wall 11 of the casing. By this construction the movable cover plate is locked to the casing while, at the same time, it is capable of free longitudinal movement with respect thereto. The end walls 12, 12 of the casing are cut away in line with the upright flanges 19^a and the horizontal shoulders 20 of the movable cover plate to provide notches 19^b, 20^b through which said flanges and shoulders may pass in the movement of said cover plate, and the end walls of the casing intermediate the said flanges 19^a terminate at a level above the inner face of said movable cover plate so that they will not interfere.

with its movement. The upright flanges 19^a, 19^a are provided with laterally extending lugs 22 spaced from the ends of the movable cover plate to limit the movement thereof within the casing, said lugs striking the end walls 12, 12 of the casing when the movable cover plate has reached the predetermined limits of its movement in either direction. It is apparent from the construction described that the movable cover plate may be placed within the casing by inserting it through the open top thereof before the fixed cover plate 14 is placed in position, and that after it has been located within the casing it can not be withdrawn therefrom until the fixed cover plate 14 has been removed.

A wear-plate 23 is carried on the inner surface of the movable cover plate 19 just as in the case of the fixed cover plate, said movable cover plate being provided with upright end flanges 24, 24, for retaining said wear-plate in place.

An antifriction device is interposed between the two cover plates of the casing to provide bearing between them. Said antifriction device comprises a plurality of rolling antifriction elements and a movable carriage in which they are inclosed, as follows: 25 30 35 40 45 50 55 60 65 70 75 80 85 90 95 100 105 110 The upper chamber 35 is divided longitudinally by a transverse rib 37 into two compartments and opposing coiled springs 38, 39 are placed in said compartments each with one end bearing against the dividing transverse wall 37 and with the other end projecting beyond the carriage and bearing against the end walls 12, 12 of the casing. The latter are preferably provided with hooks or lugs 40 adapted for supporting engagement with the proximate ends of the springs with which they engage. It is apparent that the movement of the carriage in either direction will compress one or the other of the said springs 38, 39.

In the lower chamber 36 of the carriage is placed an expansion coiled spring 41. The ends of said spring are engaged against upright lugs 42, 42, made rigid with the movable cover plate 18 and projecting up through suitable apertures in the wear-plate 23 carried thereby. The ends of said spring are also adapted for engagement with inwardly extending shoulders 43, 43 on the ends of the upright plates 29, 29 of the carriage, said shoulders being spaced apart so that the carriage may be moved longitudinally of the casing without their striking the upright lugs 42, 42 of the movable cover plate. Thus any movement of the movable cover-plate 19 will tend to compress the spring 41 against the shoulders 43 at that end of the carriage toward which said cover-plate is moving if the carriage remains stationary or moves at a less speed than that of the cover-plate 19 and causes it to move longitudinally in the casing 10 toward one or the other end thereof. This movement of the movable cover-plate imparts a rolling movement to the antifriction elements 26, 27, and they in turn by engagement with the transversely extending bars 31, impart a like movement to the carriage 28. As will be readily understood, the movement of the antifriction elements and of the carriage is only half as great as the movement of the movable cover. As a result, the coiled spring 41 will be compressed between one of the lugs 42 of the movable cover-plate at one end of the spring 41 and the shoulders 43 at the opposite end of the carriage, and that one of the coiled springs 38, located in the end of the casing toward which the carriage is traveling, will be compressed between the transverse bar 37 of the carriage and the end wall of the casing.

The operation of our improved side bearing is as follows: When, in the travel of the car to which it is applied, as in going around curves, the truck bolster shifts horizontally with reference to the body bolster and the car body tilts so as to cause the car body to approach the truck bolster, that bolster which is not attached to the casing, frictionally engages the movable cover-plate 19 and causes it to move longitudinally in the casing 10 toward one or the other end thereof. This movement of the movable cover-plate 19 permits a limited free play of each antifriction element in its compartment so that all of the antifriction elements may have a limited amount of play independently of the carriage. As a result the antifriction elements are not always brought to rest at the same points on the wear-plate, their positions of rest being capable of variation equal to the amount of play permitted them by the carriage, so that undue wear of the wear-plate at any one point or points is avoided.

The horizontal plate 30 of the carriage divides the same into upper and lower longitudinally extending chambers 35 and 36.

As shown, notches 12^y are cut in the end walls 12 of the casing for the lugs 42 to pass through in case the movable cover-plate is moved far enough to bring said lugs beyond the limits of the casing.

It will be apparent that the opposing springs 38, 39 act to center the antifriction device, comprising the carriage 28 and the antifriction elements 26, 27, with reference 10 to the casing, while the third spring 41 acts to center the movable cover-plate 19 with reference to the carriage 28 and thus with reference to the antifriction device, so that both the antifriction device and the movable 15 cover-plate will be returned to their normal positions when the pressure of the bolster against the movable cover is released, and the side bearing ceases to transmit load.

The bottom surface of the movable cover-plate is provided with longitudinally extending raised surfaces or ribs 19^x, 19^y, one under each line or row of antifriction elements 26, 27. Said ribs, as shown, are substantially of the same horizontal width as the antifriction rollers 26, 27, and act to insure the contact of the movable cover plate with the bolster engaged by it in the vertical planes of the antifriction elements alone, thus obviating any bending strain on the 25 said cover-plate tending to crush the same along a median line, that is to say, along the line where it is not supported by the antifriction elements.

It will be noted that the antifriction device holds the movable cover-plate in position within the casing and acts to prevent its withdrawal therefrom.

The movable cover-plate is made somewhat shorter in length than the casing so as 40 to leave openings 12^y at the ends of the casing, for purposes of ventilation, as clearly shown in Fig. 1.

While in describing our invention we have referred to the top and bottom side of the casing, it is to be understood that these terms, both in the description and in the claims, are to be understood only as relative terms, since apparently and as clearly pointed out in the beginning, the side bearing 45 may be attached to the truck-bolster instead of to the body-bolster, in which case that part of the casing called the top will be placed below and that called the bottom will be placed above. In addition, while in illustrating and describing one embodiment of our invention we have referred to certain details of mechanical construction and arrangement it is to be understood that the invention is in no way to be limited thereto 50 except as may be pointed out in the appended claims.

We claim as our invention:

1. In a side bearing of the class described, a casing open at top and bottom and a movable cover-plate for one of said openings 65

adapted to be inserted through the other opening thereof.

2. In a side bearing of the class described, a casing open at top and bottom, a fixed cover-plate at one open side of said casing 70 and a movable cover plate at the other open side of said casing adapted to be inserted through the first named open side thereof, and antifriction means interposed between said cover plates.

3. In a side bearing of the class described, a casing open at top and bottom, a fixed cover plate on top of said casing, a movable cover plate for the bottom of said casing, adapted to be inserted through the open top 80 thereof, means providing sliding bearing of said movable cover plate in said casing, and antifriction means interposed between said cover plates.

4. In a side bearing of the class described, 85 a casing open at top and bottom, a fixed cover plate on top of said casing, and a movable cover plate for the bottom of said casing adapted to be inserted through the open top thereof, said casing and said movable cover plate being provided with interengaging parts for supporting said movable cover plate in sliding relation with said casing, and antifriction means interposed between said cover plates.

5. In a side bearing of the class described, a casing open at top and bottom and having side and end walls, a fixed cover plate on top of said casing and a movable cover plate for the bottom of said casing adapted to be inserted through the open top thereof, the said walls of said casing being provided with longitudinally extending tracks with which said movable cover plate is adapted to engage, said cover plate being provided with stops adapted to limit the withdrawal of said cover plate from said casing longitudinally in either direction, and antifriction means interposed between said cover plates.

6. In a side bearing of the class described, a casing, a fixed top cover plate therefor and a longitudinally movable bottom cover plate therefor, said casing being provided with ventilating openings at its ends, and antifriction means interposed between said cover plates.

7. In a side bearing of the class described, a casing open at top and bottom, a fixed cover plate on top of said casing, a movable 120 cover plate for the bottom of said casing, said casing being provided with longitudinally extending parallel tracks adapted for supporting engagement with said movable cover plate and said movable cover plate terminating at its ends short of the ends of the casing, providing ventilating openings, and antifriction means interposed between said cover plates.

8. In a side bearing of the class described, 130

in combination with a casing, a movable cover plate for the bottom of said casing, an antifriction device longitudinally movable in said casing, opposing resilient devices interposed between said antifriction device and the casing to resist the longitudinal movement thereof in either direction, and an additional resilient device interposed between said antifriction device and said movable cover plate adapted to oppose the longitudinal movement of said cover plate with reference to said antifriction device in either direction.

9. In a side bearing of the kind described, in combination with a casing, a movable cover-plate for the bottom of said casing, an antifriction device longitudinally movable in said casing, opposing springs acting between said casing and said antifriction device to resist the longitudinal movement of said antifriction device in either direction, and an additional spring located in a different horizontal plane but in the same vertical plane with said first two named springs, said additional spring being adapted to resist relative longitudinal movement between said movable cover plate and said antifriction device in either direction.

10. In a side bearing of the kind described, in combination with a casing, a movable cover-plate on the bottom of said casing, and an antifriction device longitudinally movable in said casing, said antifriction device comprising a carriage and antifriction elements arranged in rows on each side of the median line of said carriage, and said carriage having laterally extending, longitudinally spaced bars providing compartments one for each of said antifriction elements.

11. In a side bearing of the kind described, in combination with a casing, a movable cover-plate on the bottom of said casing, an antifriction device longitudinally movable in said casing and comprising a carriage provided with longitudinally spaced rows of compartments on either side of the median line thereof and a plurality of antifriction elements, one in each of said compartments, said antifriction elements having limited play within said compartments.

12. In a side bearing of the kind described, in combination with a casing, a movable cover-plate on the bottom of said casing, an antifriction device longitudinally movable in said casing and comprising a carriage provided with longitudinally spaced rows of compartments on either side of the median line thereof and a plurality of antifriction elements, one in each of said compartments, opposing resilient members located in a plane between said rows of compartments adapted to resist the movement of said carriage in either direction in said casing, and an additional resilient member located in a different horizontal plane but in the same vertical plane with the said first two named resilient members adapted to resist relative movement between said movable cover plate and said carriage.

13. In a side bearing of the kind described, in combination with a casing, a movable cover-plate having sliding bearing in said casing, a carriage longitudinally movable in said casing, antifriction elements arranged in rows at either side of the median line of said carriage, opposing springs bearing between a fixed part of said carriage and the ends of the casing, an additional spring located below the planes of the first two named springs, said movable cover plate being provided with upright lugs adapted to engage against the ends of said third spring and said carriage being provided with laterally spaced lugs between which said first named lugs are adapted to pass which are also engaged against the ends of said additional spring.

14. In a side bearing, a casing, a longitudinally movable cover for said casing, a longitudinally movable carriage in said casing, and an antifriction element in said carriage, said antifriction element being capable of limited play within the carriage.

In testimony, that we claim the foregoing as our invention we affix our signatures in the presence of two witnesses, this 25th day of October A. D. 1912.
